BUTTON CLAMP

Samuel W. Avis, deceased, late of Wellesley, Mass., by Harriette M. Avis, administratrix, Wellesley, Mass., assignor to The Reece Button Hole Machine Company, Boston, Mass., a corporation of Maine

Application May 19, 1943, Serial No. 487,569

14 Claims.

(Cl. 112—114)

This invention relates to machines for sewing buttons or otherwise attaching buttons to work, and particularly to the clamps for positioning and holding the buttons for the action of the attaching instrumentalities.

The invention has for its general object to provide an improved, smoothly operating but simply constructed and inexpensive button holder or clamp for accurately holding and positioning a substantially flat perforated button. It is also an object to provide an improved and simply constructed mechanism for automatically opening the clamp in order to release the button when the clamp is raised from the work. The invention will best be understood from the following description of an illustrative embodiment thereof shown in the accompanying drawings.

In said drawings:

Fig. 1 is a side elevation, partly broken away, of a portion of a button sewing machine equipped with a button clamp embodying the invention;

Fig. 2 is a front elevation of said button clamp;

Fig. 3 is a plan view of said button clamp;

Fig. 4 is a vertical section along the lines 4—4 of Figs. 2 and 3;

Fig. 5 is a perspective view of a part of said clamp, and

Fig. 6 is a perspective view of another part of said clamp.

While the invention is not limited in its application to any particular type of button attaching machine, it is for convenience illustrated in connection with a button sewing machine of the character shown and described in United States Letters Patent to Franklin A. Reece, No. 2,158,200, issued May 16, 1939, wherein all of the lateral movements necessary to attach either a two-hole or a four-hole button are imparted to the stitch-forming instrumentalities as distinguished from the work-holding instrumentalities. Said machine comprises a base 15 supporting a work plate 16 and an overhanging head 17 in which is suitably guided a needle bar 18 carrying a needle 19 which cooperates with underthread or looper mechanism 20 to attach to work W supported on the work plate 16 a flat perforated button B held by a combined presser foot and button clamp assembly C. The assembly C is normally pressed toward the work W to clamp the latter on the work plate 16 and hold the button B in properly positioned relation thereto, but may be raised, before and after the attaching operations, to permit the insertion, removal or positioning of the work and the insertion or removal of successive buttons. As shown in the drawings, said assem-

bly is provided with a short upright stem 21 connected by an arm 22 with a slide 23 guided for vertical movement in the head 17. The slide 23 is normally held downward to urge the combined 5 clamp and presser foot against the work by a spring 24 associated with a lever 25 having one end thereof adapted to engage a pin 10 carried by the slide 23 and the other end connected, as by a chain 26, to a treadle 27 which may be depressed to rotate the lever 25 clockwise in Fig. 1 against the tension of said spring 24 to move the slide 23 upwardly and thereby raise the assembly.

To prevent rotation of the slide 23 (and consequently rotation of the assembly C) said slide 23 is provided with a rearwardly extending arm 50 which terminates in a hook-shaped end 51 adapted to slidably engage an upright 52 secured to the side of the machine.

In the present invention the stem 21 supports three jaw carrying members 60, 61 and 62. The member 60 is provided with a slot 63 adapted to receive a collar 64 mounted on the stem 21. The slot 63 allows said member to slide in a forward or backward direction. The member 60 is also provided with lateral arms 65 having therein slots 66 and 67, the longitudinal axes of which are perpendicular to the longitudinal axis of said slot 63. The two jaw carrying members 61 and 62 are angular in form (see Fig. 6) and each is provided with a hole 68 in one arm thereof and each is provided with a pin 69 in its apex or angle. The holes 68 are adapted to receive the collar 64, so that the carrier members 61 and 62 are pivotally mounted on said collar 64 and extend laterally therefrom on either side. The collar 64 has a ring 70 disposed above the member 60 and a ring 71 disposed below the member 62. These rings serve to hold said members 30 against vertical movement independent of the stem 21. The pins 69 are slidably received in the slots 66 and 67 formed in the lateral arms 65 of the carrying member 60. The member 60 is provided with a button holding jaw 72 and the members 61 and 62 are each provided with button holding jaws 73 and 74. Each of these jaws 35 (see Fig. 4) is constructed in the form of an angle. The jaws 73 and 74 are adapted to receive the button on the inside surface of the angle formed; the jaw 72 receives the button on the outer surface of the angle. These jaws clamp a button placed between them by pressing inwardly and downwardly upon it, the button receiving underneath support from the top surface 40 of a presser foot 75 carried by the member 60.

The lower surface of said presser foot may be used to clamp the work *W* when the assembly is in operative position. The presser foot *75* and the jaws *72*, *73* and *74* are secured to the members *60*, *61* and *62* as by screws *16*.

Secured to the stem *21* is a rod *77* which extends rearwardly over the member *60* and extends through a hole *78* in a flange *79* on the rear end of the member *60* so that it serves as a guide for the member *60*. A spring *80* around the rod *77* is held compressed between a collar *81* secured to the rod *77* as by a clamping screw *82*, and a bracket *83* secured to said member *60* as by rivets *84*. A stud *85* is screwed through the stem *21*, the rearwardly extending end thereof serving to limit the forward movement of the bracket *83* under the impulse of the spring *80* and thus likewise serving to limit the forward movement of the member *60*. A toggle *86* comprises paired links *87* and *88* joined by a transverse pin *89* carrying a sleeve *90*, the links of the several pairs being (preferably integrally) connected by bridge pieces *87a* and *88a*, respectively. The links *87* are pivoted at *91* on opposite sides of the stem *21*, and links *88* are pivoted at *92* on spaced ears *93* extending from the flange *79* formed on the rear end of the carrying member *60*, so that the toggle *86*, as well as the rod *77*, serves to guide the member *60* for rectilinear movement. The toggle *86* is normally held in the relatively collapsed position as shown in Fig. 4 under the impulse of the spring *80*, at which time the member *60* is moved forwardly and exerts pressure on the pins *69* to rotate the members *61* and *62* in a forward direction so that the jaws *72*, *73* and *74* are all forced inwardly toward each other in button clamping position. When the sewing operation is completed and the clamp assembly is raised by depressing the treadle *21*, the sleeve *90* is brought into contact with a stud *94* in the overhanging arm *17* of the machine, thereby causing the stud *94* to straighten or flatten the toggle to counteract spring *80* and move the member *60* rearwardly. As the member *60* moves rearwardly it acts, through the slots *66* and *67* and pins *69*, to rotate the members *61* and *62* backwardly so that the jaws *72*, *73* and *74* are separated or moved apart into button-releasing or button-receiving position.

Buttons may be attached closely to the cloth or may be spaced therefrom with a neck of thread extending between cloth and button. When buttons are sewn close to the cloth, the presser foot *75* is used to hold the work, but when necks of varying lengths are desired, an adjustable auxiliary presser foot *100* may be employed. This adjustable presser foot, which acts as a spacer, is provided with a stud *101* threaded into the lower end of the stem *21*, the threads having a relatively flat pitch. The extent to which the stud *101* is screwed into the stem *21* determines the length of the neck of thread between the cloth and the button. A lock nut *102* secures the stud *101* in position after the presser foot *100* has been properly adjusted.

What is claimed is:

1. In a sewing machine for attaching buttons, button clamping means comprising three relatively movable members each having a button clamping jaw, one of said members being guided for reciprocating movement and the others being mounted to swing about a common axis, and means connecting said members for causing the other members to pivot about their common axis

so that all three button clamping jaws are simultaneously advanced into button clamping position and simultaneously withdrawn into button releasing position when said first named member is reciprocated.

5 2. In the machine defined in claim 1, a spring for moving the reciprocating member in one direction and a toggle mechanism for moving said member in the opposite direction.

10 3. In a sewing machine for attaching buttons to work, button clamping means comprising three relatively movable members each bearing a button clamping jaw, one of said members being guided for reciprocating movement, the other two of said members being pivotally mounted to swing about a common axis in the same plane as the longitudinal axis of movement of said reciprocating member, means associated with said reciprocating member for imparting a pivotal movement to said other members simultaneously with said reciprocating movement whereby said button clamping jaws are moved in coordination into and out of button clamping position.

25 4. In a sewing machine for attaching buttons to work, button clamping means comprising three relatively movable members each bearing a button-clamping jaw, one of said members being guided for reciprocating movement, the other two of said members being pivotally mounted to swing about a common axis in the same plane as the longitudinal axis of movement of said reciprocating member, means associated with said reciprocating member for imparting a pivotal movement to said other members simultaneously with said reciprocating movement whereby said button clamping jaws are moved in coordination into and out of button clamping position, a spring for moving said reciprocating member in one direction, and a toggle for moving said reciprocating member in the other direction against the action of said spring.

30 5. In a sewing machine for attaching buttons to work, a presser foot for holding said work, means for lifting said presser foot to release said work, button clamping means comprising a slideable reciprocating member having laterally extending arms and a pair of laterally disposed clamping members having a common pivotal axis in the plane of the longitudinal axis of movement of said reciprocating member and operatively connected to said lateral arms of the reciprocating member to receive therefrom a pivotal movement coordinated with said reciprocating movement, a button-clamping jaw secured to each of said members, a spring for moving said reciprocating member into button clamping position, a toggle for moving said reciprocating member against the action of said spring, and means operable on the raising of said presser foot for operating said toggle.

35 6. A button clamp comprising three relatively movable members having button holding jaws secured thereto adjacent their outer ends, means for guiding one of said members for substantially rectilinear movement, the other two members being pivoted at their inner ends to swing about a common axis, and pin and slot connections between said first named member and said other members intermediate the ends of the latter whereby rectilinear movement of said first named member causes said other members to swing about said axis.

40 7. A button clamp comprising a supporting stem, three relatively movable members having

button holding jaws secured thereto adjacent their forward ends, means for guiding one of said members for substantially rectilinear movement, said means including a toggle connected at one end at spaced points to said stem and at the other end at spaced points to said member, and means associated with said member for giving the other two members a rotative movement in timed relation to the rectilinear movement of the first to cause said jaws to move in unison into and out of button clamping position.

8. In a button sewing machine, a work plate, a button holding assembly movable toward and away from said work plate, said assembly including a plurality of button holding or clamping jaws relatively movable toward and away from one another to clamp and release a button, means including a toggle for moving said jaws away from one another, and means engaged by said toggle when said assembly is moved away from the work plate to cause said toggle to automatically move said jaws away from one another.

9. In a button sewing machine, a work plate, a work clamping and button holding assembly movable toward and away from said work plate to clamp and release the work, said assembly including a plurality of button holding or clamping jaws relatively movable toward and away from one another to clamp and release a button, means including a toggle for moving said jaws away from one another, and means engaged by said toggle when said assembly is moved away from the work plate to cause said toggle to automatically move said jaws away from one another.

10. In a button sewing machine, a work plate, a button holding assembly movable toward and away from said work plate, said assembly including a plurality of button holding or clamping jaws relatively movable toward and away from one another to clamp and release a button, means including a toggle for moving said jaws away from one another, and an abutment engaged by the joint of said toggle when said assembly is moved away from the work plate to straighten said toggle and cause the same to automatically move said jaws away from one another.

11. In a button sewing machine, a work plate, a button holding assembly movable toward and away from said work plate, said assembly including a plurality of button holding or clamping jaws relatively movable toward and away from

one another to clamp and release a button, a spring acting normally to move said jaws toward one another, means including a toggle for moving said jaws away from one another, and means engaged by said toggle when said assembly is moved away from the work plate to cause said toggle to automatically move said jaws away from one another.

12. In a button sewing machine, a work plate, a button holding assembly movable toward and away from said work plate, said assembly including a support and a plurality of jaw carrying members movably mounted thereon, said members being interconnected for movement in unison to move the jaws carried thereby toward and away from one another to clamp and release a button, a toggle interposed between said support and one of said members, and means engaged by said toggle when said assembly is moved away from the work plate to straighten said toggle and thereby cause said jaws to move away from one another.

13. In a button sewing machine, a work plate, a button holding assembly movable toward and away from said work plate, said assembly comprising three relatively movable members having button holding jaws secured thereto adjacent their forward ends, said members being interconnected for movement in unison to move said jaws toward and away from one another to clamp and release a button, means including a toggle for guiding one of said members for substantially rectilinear movement and for moving the same in the direction to cause said jaws to release the button, and means engaged by said toggle when said assembly is moved away from the work plate to cause said toggle to automatically move said jaws.

14. In a button attaching machine, button clamping means comprising three relatively movable members carrying button holding jaws, means including a toggle for guiding one of said members for substantially rectilinear movement, the other two of said members being mounted to swing about a common axis, and means connecting said members for causing said last named members to pivot about their common axis when said first named member is moved rectilinearly.

HARRIETTE M. AVIS,
